UNITED STATES PATENT OFFICE

FRED S. CARR, OF NEWTON, MASSACHUSETTS, ASSIGNOR, BY MESNE ASSIGNMENTS,
TO UNITED-CARR FASTENER CORPORATION, OF CAMBRIDGE, MASSACHUSETTS, A
CORPORATION OF MASSACHUSETTS

SEPARABLE SNAP FASTENER

Application filed April 21, 1927. Serial No. 185,436.

My invention aims to provide improvements in separable snap fasteners of the type particularly, though not exclusively, adapted for fastening carpets and the like to floors.

5 In the drawings, which illustrate a preferred embodiment of the invention:—

Figure 1 is a plan view of a corner portion of a carpet showing the underlying fastening means in dotted lines;

10 Fig. 2 is a section taken on the line 2—2 of Fig. 1, the stud being shown in elevation;

Fig. 3 is a plan view of the socket member before attachment;

15 Fig. 4 is a side elevation of the socket member shown in Fig. 3; and

Fig. 5 is a section taken on the line 5—5 of Fig. 1, showing the normal relation of the socket to the stud when being engaged therewith.

20 Referring to the embodiment of my invention illustrated by the drawings, I have shown a simple form of fastener socket A secured to the under side of a carpet 1 for engagement with a stud B secured to the floor 2.

25 The socket A is in the form of an annular casing pressed from a single piece of metal. It is provided with an outer wall 3 parallel with the axis of the socket and a pair of opposed jaw portions 4 which curve inwardly and upwardly from the lower edge wall and 30 terminate at the stud-receiving aperture 5, as shown in Figs. 2 and 3. Attaching prongs 6 extend upwardly from the upper edge of the wall 3 and are preferably bent outwardly and downwardly, after passing through the carpet, to engage over the warp and weft threads, as shown in Figs. 2 and 5. Ears 7 extend inwardly from the upper edge of the wall 3 between the prongs 6 and bear against the under 35 side of the carpet (Fig. 2) to prevent the carpet from interfering with the action of the casing when being engaged with or disengaged from the stud B.

40 Substantial spaces 8 are provided between the side edges 9 of the jaws 4, and the wall 3 is severed by a slit 10 adjacent to one of these spaces to permit lateral contraction and expansion of the wall when the socket is being engaged with or disengaged from a stud. 45

50 These spaces are important inasmuch as the

space opposite the slit 10 leaves the wall 3 of the casing free to maximum flexing adjacent to where the greatest bend occurs and thereby reduces to a minimum the possibility of the socket becoming "set". Furthermore, the 55 spaces reduce the width of the stud-engaging ends of the jaws 4 to a point where one jaw may engage beneath the head 11 of the stud (Fig. 5), before it is necessary to expand the wall 3 so that the other jaw may engage the 60 neck 12 of the stud B. Thus, when engaging the socket with and disengaging it from the stud B, the wall 3 of the socket is only required to expand one half as much as it would if the jaws were of such dimensions that one 65 could not be engaged with the neck 12 without expanding the wall 3.

The jaws 4 are curved to facilitate entrance of the stud B in the stud-receiving aperture 5 and are substantially inflexible so that enlargement of the aperture occurs by spreading the jaws laterally with the wall 3 to permit the head 11 of the stud therethrough.

I do not wish to be limited to the specific embodiment of my invention illustrated and 75 described, my invention being best defined in the following claims.

Claims:

1. A fastener socket comprising a stud-receiving casing having a wall parallel with the axis of the casing, said wall being severed at one side to permit lateral expansion thereof, a pair of oppositely disposed stud-engaging jaw portions extending inwardly from said wall and terminating at a stud-receiving 85 aperture, said jaws being laterally shiftable with said wall to permit enlargement of the stud-receiving aperture for the head of a stud to pass therethrough, the side edges of said jaws being spaced from each other to provide 90 spaces of substantial length adjacent to said wall, and adjacent to the stud-receiving aperture thereby permitting engagement of the socket with a stud by hooking one jaw into engagement with the neck of the stud and 95 then pressing the other jaw over the head to engage the neck, said first jaw acting as a fulcrum, and one of the spaces between said side edges of the jaws being located opposite the severed portion of said wall to provide sub- 100

stantial resiliency to said wall where the greatest bend occurs.

2. A fastener socket comprising a stud-receiving casing having a wall parallel with the axis of the casing, said wall being severed at one side to permit lateral expansion thereof, a pair of oppositely disposed stud-engaging jaw portions extending inwardly from said wall and terminating at a stud-receiving aperture, said jaws being laterally shiftable with said wall to permit enlargement of the stud-receiving aperture for the head of a stud to pass therethrough, the side edges of said jaws being spaced from each other to provide spaces of substantial length adjacent to said wall, and adjacent to the stud-receiving aperture thereby permitting engagement of the socket with a stud by hooking one jaw into engagement with the neck of the stud and then pressing the other jaw over the head to engage the neck, said first jaw acting as a fulcrum and one of the spaces between said side edges of the jaws being located opposite the severed portion of said wall to provide substantial resiliency to said wall where the greatest bend occurs, a plurality of ears extending inwardly at right angles to said wall for engagement of one face of a flexible socket-carrying medium to maintain the carrying medium above the plane of the wall from which said means extend to prevent interference with the operation of the jaw portions and a plurality of attaching prongs extending upwardly from said casing between said ears for securing said casing to its carrying medium.

In testimony whereof, I have signed my name to this specification.

FRED S. CARR.
